APPARATUS FOR MARINE OPERATIONS

William T. Guenzel, Houston, Tex., assignor, by
mesne assignments, to Standard Oil Develop-
ment Company, Elizabeth, N. J., a corporation
of Delaware

Application July 29, 1949, Serial No. 107,408

7 Claims. (Cl. 61—46)

1
The present invention is directed to apparatus which is suitable for use and operations in a body of water. More particularly, the invention is directed to apparatus for supporting a platform and the like suitable for use in marine operations. In its more specific aspects, the invention is directed to apparatus which may be submerged or raised from the ocean floor and is adapted to supporting a platform and the like.

Prior to the present invention it has been old to drive piling and construct various structures supported on the ocean floor on which platforms and the like may be built and from which drilling operations may be conducted. It has also been known to build oil well derricks and the like on barges and to sink or partially sink the barges to the bottom of a body of water and from the sunken or partially sunken vessel conduct drilling operation as conventionally conducted on land. It has also been known to prefabricate structures suitable to load on barges and various vessels and then to transfer the prefabricated structure to the location at sea where it is to provide support for oil well drilling operations.

All of the foregoing expedients are disadvantageous in that they are expensive and furthermore, present hazards when operations are conducted in water over 50 feet in depth. Thus, in waters in the Gulf of Mexico ranging in depths from 50 to 200 feet, it is not feasible to build large structures ashore and to transport them on barges, since the area exposed to wind and waves is so great and the structures so unwieldy that there is danger of capsizing them. Driving piling and constructing platforms thereon in waters ranging in depth from 50 to 200 feet also presents hazards and disadvantages which may make them impractical.

It is, therefore, the main object of the present invention to provide an improved apparatus which may be constructed ashore and safely towed to the location at sea or offshore where the drilling operation is to be conducted.

Another object of the present invention is to provide an improved structure which may be prefabricated ashore, towed to its location and submerged to provide a support for a platform and the like.

Another object of the present invention is to provide a structure which may be easily submerged and raised.

Still further objects of the invention will become apparent from reading the description taken with the drawing of which

2
Fig. 1 is an end view of the apparatus of the present invention in a horizontal position for towing to the location;

Fig. 2 is an end view of the apparatus of Fig. 1 after it has been submerged in a vertical position from which the operation is to be conducted;

Fig. 3 is a view of the apparatus of Fig. 2 taken along the lines III—III.

Fig. 4 is an end view of another embodiment of the invention showing a different type of buoyant member and means for supporting same; and

Fig. 5 is a detail of the apparatus of Figs. 1, 2, 3 and 4 showing means for coupling the buoyant members together and means for admitting and discharging water therefrom.

In the several figures of the drawing identical numerals will be employed to designate identical parts.

The principal parts of the apparatus of the present invention include a pair of structure members 11 rigidly attached to base or buoyant members 12. Each of structure members 11 is provided with removable buoyant members 15. The apparatus is adapted to support decks or platforms 14.

Referring now to Fig. 1, numeral 11 designates a pair of prefabricated template frame structures which are rigidly attached to base buoyant members or pontoons 12. Pontoons 12 are hinged together with a loose pin hinge 13 which is shown in the open position and the structures 11 are folded to the horizontal position with the base buoyant members 12 assuming a vertical position. It is understood, of course, that when the structure members 11 and the buoyant members 12 are in use, the structure members 11 will assume a vertical position and the buoyant members 12 will assume a horizontal position and the hinges 13 will be in the closed position.

The structure members 11 may be provided with a plurality of decks 14 as desired. The structure members 11, when in the horizontal position as shown on Fig. 1, are supported by the pontoons 12 and second buoyant members 15 which are hinged to the structure members 11 with hinges 16. The second buoyant members 15 may be compartmented pontoons provided with suitable ballasting and are designed to be removed by uncoupling the hinges 16. The hinges 16 are designed to allow the structure members 11 to pivot about the hinges 16, while the members 15 remain in a substantially horizontal position and provide buoyancy for the structure members 11. The structure members 11 and buoyant members 12, have attached there-

to a plurality of conduits 17 through which piling may be driven to maintain the structure in a vertical position as shown in Fig. 2. The buoyant members 12 are compartmented, sized and shaped to provide the desired buoyancy and may be suitably coupled together by couplings 18 when in a towing position as shown in Figs. 1 and 5.

Referring to Fig. 2 wherein an end view of the apparatus of the present invention is shown submerged to the bottom of a body of water, it will be seen that piling 19 may be driven into conduits 17 to anchor the structure at its location.

The embodiment of Fig. 4 is identical to the embodiments of Figs. 1 to 3 with the exception that the buoyant members supporting the structure when in a horizontal position are elliptical rather than rectangular in shape. In this embodiment the horizontal member may be elliptical, as shown, or cylindrical in shape. Thus structure members 11 are provided with brackets 30 carrying a sling 31 which is thrown around a buoyant member 32 and lashed into the curved portion 33 of bracket 30 to allow the structures 11 to pivot around the buoyant members 32 in a manner similar to that described with respect to Figures 1 and 2.

Fig. 5 shows a detail of the pontoon members 12 with a cutaway portion of the structure 11 attached thereto. In Fig. 5 it will be noted that the buoyant members 12 may be rigidly connected together by coupling members 18 to assure rigidity of the structure when in a towing position and when the buoyant members 12 are in a vertical position and the hinge 13 is in the open position. In Fig. 5 means are shown for admitting and discharging water to the buoyant members 12. This is accomplished by a plurality of sea cocks 41 arranged along the bottom of the buoyant members 12 and operated by remote control from platforms 14. There is also provided a plurality of inlets 42 for admitting air or other gaseous media under pressure to the buoyant members 12 to discharge water therefrom. Inlets 42 are connected by piping to equipment and suitable manifolds for controlling the ballasting or dewatering of the pontoons 12 and also provide means for escape of air from the buoyant members 12 when water is being admitted thereto through sea cocks 41.

The apparatus in the present invention is constructed in two parts which are adapted to dovetail and to form one structure and may be bolted or connected together at points above water as shown in Fig. 2 where it will be seen that the structure 11 may be bolted or coupled together at connections 20.

In locating the apparatus of the present invention a pair of structures 11, adapted to dovetail and to connect together as described, is prefabricated on land on a pair of hinged pontoons or buoyant members similar to buoyant members 12. These pontoons may be hinged together with loose pin hinges and the structure to which has been attached removable pontoons or buoyant members 15 turned on a side with the hinge in the open position and floated in the water by means of the buoyancy of the buoyant members 12 and 15. The couplings or connections 18 are rigidly fixed and the whole structure in the open position, which may be as much as 300 feet or more depending on the depth of the water in which it is to be located, towed to the site which has previously been prepared. It may be necessary to level the bottom of the sea at which

the apparatus is to be located and this may be done by various means well known to the art. Assuming that the apparatus has reached its position where it is to be located and is in the position shown in Figs. 1 and 5, the couplings 18 are disengaged and sea cocks 41 are opened allowing water to be admitted to the buoyant members 12. At the same time the tugs or boats towing the apparatus may exert tension on the structure 11 at each end to assist in controlling the closing or opening of the hinges 13. As the water rushes into the buoyant members 12, these base members gradually sink. As a result, the structure members 11 pivot about the hinges 16 or the pontoons 32 and slowly assume a vertical position as shown in Fig. 2. While the base members 12 are being submerged, the buoyant members 15 or 32 provide stability and support for the structure. The structure in a vertical position with the hinges 13 closed is then seated on the bottom of the body of water in which it is being submerged by ballasting pontoons 12 and 15 or 32 as required. Once the apparatus of the present invention has reached the position indicated in Fig. 2, piling may then be inserted in the conduits 17 defined by the structure 11 and the buoyant members 12 and driven therethrough into the ocean floor to anchor and support or provide rigidity for the whole structure.

After the apparatus has been located, the buoyant members 15 and 32, as the case may be, may be disconnected and towed ashore for re-use in supporting other similar structures for towing to a desired location.

When the apparatus of the present invention is to be moved, this may be accomplished by reversing the process. The piling 19 would be withdrawn and the buoyant members 15 and 32 would be attached to the structure. Air or other gases under pressure would be admitted to the inlet lines 42 and water would be forced under pressure out of the sea cocks 41 which would exert a jetting action on the ocean floor and cause the buoyant members 12 to be released therefrom. As water is discharged from the buoyant members 12, the structure would gradually rise and pivot around buoyant members 15 and 32 until the structure 11 was resting thereon and supported in the water with the apparatus again assuming a horizontal position shown in Figs. 1 and 5.

It will be seen from the foregoing description, taken with the drawing, that apparatus has been described which may be constructed on land and located at sea with a minimum of effort. It can also be seen that apparatus has been described which may be moved from one location to another without difficulty. While the apparatus of the present invention has particular application to provide a platform from which oil well drilling operations may be conducted, it is also adaptable to support tanks and other structures at sea. For example, during the recent war, in the Thames estuary in England, it was necessary to construct pill boxes to prevent depredations of enemy aircraft in sowing mines. The present invention would be readily adaptable to support such structures.

The device of the present invention has been described with respect to a template structure, but it will be readily understood that it is adaptable to any prefabricated structure rigidly attached to pontoons, barges, other buoyant members, and the like.

It will be apparent to the skilled workman that

the pontoon or buoyant members may be constructed in compartments and that the buoyant members 12, 15 or 32 may be suitably ballasted when the apparatus is being towed, submerged or raised. It is within the purview of my invention to construct the apparatus of the present invention of timber or various structural metals. It will be desirable, however, to choose a constructional material which will resist the corrosive action of sea water and sea air.

The nature and objects of the present invention having been completely described and illustrated, what I wish to claim as new and useful and to secure by Letters Patent is:

1. Apparatus for supporting a platform and the like adapted for marine operations which comprises, in combination, a first pair of buoyant members, a pair of template structures, each one of which is rigidly attached at a lower end to one of said buoyant members and at an upper end thereof to one of a pair of platforms supported thereby adapted to form together when connected one substantially horizontal platform when said first pair of buoyant members are in a horizontal position, connection means for said platforms adapted to dovetail same when the platforms assume a horizontal position, hinging means connecting said buoyant members and adapted to assume open and closed positions, said structures being in a substantially horizontal position and said buoyant members and said platforms being in a substantially vertical position when said hinging means are in an open position and said structures being in a substantially vertical position and said buoyant members and said platforms being in a substantially horizontal position when said hinging means are in a closed position, a second pair of buoyant members each one of which is pivotably mounted to one of said structures at a point intermediate the lower and the upper ends thereof and adapted to support said structures in water with said first pair of buoyant members in the vertical position, and means for submerging and raising both pairs of buoyant members.

2. Apparatus in accordance with claim 1 in which said second buoyant members are removably mounted on said structures.

3. Apparatus in accordance with claim 1 in which said first and second buoyant members 50 are pontoons.

4. Apparatus for supporting a platform and the like adapted for marine operations which comprises, in combination, a first pair of buoyant members, a pair of template structures each one of which is rigidly attached at a lower end to one of said buoyant members and at an upper end thereof to one of a pair of platforms supported thereby adapted to form together when connected one substantially horizontal platform 60 when said first pair of buoyant members are in a horizontal position, hinge means connecting said buoyant members and adapted to assume open and closed positions, said structures being in a substantially horizontal position and said buoyant members and platforms being in a substantially vertical position when said hinging means are in an open position and said struc-

tures being in a substantially vertical position and said buoyant members and platforms being in a substantially horizontal position when said hinging means are in a closed position, a second 5 pair of buoyant members each one of which is pivotably mounted to one of said structures at a point intermediate the lower and upper ends thereof and adapted to support said structures in water with said first pair of buoyant members 10 in the vertical position, first coupling means mounted on and adapted to connect said first pair of buoyant members when said first buoyant members are in the vertical position, second coupling means mounted on and adapted to connect said structures when said structures are in a vertical position, and means for submerging and raising said first pair of buoyant members.

5. Apparatus in accordance with claim 3 in which said second buoyant members are removably mounted on said structures.

6. Apparatus for supporting a platform and the like adapted for marine operations which comprises a first pair of buoyant members, a pair of template structures defining with said buoyant 25 members a plurality of conduits adapted to receive piling, each one of said structures being rigidly attached at a lower end to one of said buoyant members and at an upper end thereof to one of a pair of platforms supported thereby adapted to form together when connected one substantially horizontal platform when said first pair of buoyant members are in a horizontal position, connection means for said platforms adapted to dovetail same when the platforms assume a horizontal position, hinging means connecting said buoyant members and adapted to assume open and closed positions, said structures being in a substantially horizontal position and said buoyant members and platforms being in a substantially vertical position when said hinging means are in an open position and said structures being in a substantially vertical position and said buoyant members and platforms being in a substantially horizontal position when said hinging means are in a closed position, a second 35 pair of buoyant members each one of which is pivotably mounted to one of said structures at a point intermediate the lower and upper ends thereof and adapted to support said structures in water with said first pair of buoyant members in the vertical position, and means for submerging and raising said first pair of buoyant members.

7. Apparatus in accordance with claim 6 in which said second buoyant members are removably mounted on said structures.

WILLIAM T. GUENZEL.
